UNITED STATES PATENT OFFICE.

HENRY E. WALLIS, OF CHICAGO, ILLINOIS, ASSIGNOR OF ONE-HALF TO
WILLIAM E. NILES, OF SAME PLACE.

FURNACE.

SPECIFICATION forming part of Letters Patent No. 608,995, dated August 9, 1898.

Application filed December 5, 1896. Serial No. 614,540. (No model.)

To all whom it may concern:

Be it known that I, HENRY E. WALLIS, a citizen of the United States, residing at Chicago, in the county of Cook and State of Illinois, have invented certain new and useful Improvements in Furnaces, of which the following is a full, clear, and exact specification.

The primary object of my invention is to provide improved means whereby a complete dumpable section of a grate composed of a series of such dumpable sections may be brought opposite the stoking-door each time the door is opened, whereby the fresh fuel thrown in will lodge substantially on but one of the sections, and hence substantially all of the fuel will be consumed on each section before any of it or the ashes thereon are ready to be dumped, and as a result when a section is dumped the unconsumed fuel will not be wasted nor will any of the remaining sections be occupied with any considerable amount of ashes or consumed fuel mixed with unconsumed fuel.

A further object of my invention is to cause a thorough coking of the fuel at the forward or stoking side of the fire-box before its conveyance to the rear or hotter region of the fire-box.

With these ends in view my invention consists in certain features of novelty by which the said objects and certain other objects hereinafter appearing are attained, all as fully described with reference to the accompanying drawings and more particularly pointed out in the claims.

In the said drawings, Figure 1 is a plan sectional view of my improved furnace, taken on the line 3 3, Fig. 2. Fig. 2 is a vertical longitudinal section thereof, taken on the line 40 2 2, Fig. 1. Fig. 3 is a transverse sectional view taken on the line 3 3, Fig. 1; and Fig. 4 is a front elevation showing the apparatus whereby the opening of the door and the simultaneous rotation of the grate are effected.

In carrying out my invention I employ a fire-box, which is preferably provided with a circular fire-pot or with circular walls 1, so as to conform with the grate, which is also circular and which is composed of a number 45 of independently-tilting sections 2 3 4 5 6 7, each having at its outer end a journal 9, sup-

ported upon a marginal ring 10, and at its inner end a journal 11, supported in a common hub 12, connected to the ring 10 by a number of spokes 13. The grate-sections 55 2 3 4, &c., are segmental in form and are situated between the spokes 13, as more clearly shown in Fig. 1, and being thus pivoted on the hub 12 and ring 10 each is capable of tilting independently of the other when it is 60 desired to dump the whole or any portion of the fire. In order that each section may be held against accidental tilting or dumping, each may be provided at one side or corner with a lug or stop 14, adapted to engage under one of the spokes 13, as shown in Fig. 1. Each of the outer journals or trunnions 9 is provided with a key-post 15, whereby the grate may be tilted when the particular section is brought opposite the stoking-aperture 70 or fire-door 16, as will be understood, the ring 10 being cut away for the accommodation of the key-posts 15, as shown at 17, and the seats or notches in which the trunnions or journals 9 11 are supported being open at their upper 75 sides, so that the grate-sections may be readily removed at will when it is desired to repair or renew them.

The central hub 12 is supported upon an upright pivot 18, which is formed on or secured 80 to a transverse beam 19, having its ends suitably supported in the masonry of the furnace-walls below the grate. This pivot 18 sustains the major part of the weight of the grate and permits it to readily revolve, while the outer 85 edge of the grate is held against deflection by means of a number of brackets 20, set into the wall or masonry of the furnace and bearing under a flange 21, projecting from the outer side of the ring 10, such flange 21 being also 90 cut away, like the ring 10, for the accommodation of the wrench when applied to the key-posts 15, but such cut-away portion being of less width than the brackets 20, so as to avoid the possibility of the brackets engaging 95 therein.

In the space between the upper surface of the marginal ring 10 and the lower edge of the fire-pot 1 is inserted a ring 48, provided on its under side with a number of teeth which 100 project downwardly toward without actually touching the ring 10 and prevent the cinders

and fuel from escaping, while at the same time permitting the draft to rise from the ash-pit and pass into the fuel on the grate around the outer edges of the ring 10.

- 5 The under side of the ring 10 is provided at suitable intervals, preferably one for each of the grate-sections 5, with a number of teeth or notches 22, whose one side is abrupt or precipitous, while the other is inclined, as shown 10 more clearly in Figs. 2 and 3, and pivoted under the grate upon the pivot 18 is a pawl or dog whose one end 23 is adapted to engage with the teeth 22, and thus impart rotation to the grate, while the other end of the dog is 15 provided with a weight 24, which holds the end 23 into engagement with the teeth 22 and at the same time permits the end 23 to be deflected sufficiently to pass over the inclined side of the tooth and engage with its abrupt 20 side, as will be understood. The dog 23 is supported by the beam 19, and in order that its ends may rise and fall in the manner described the interior of its hub is flared or rounded, as shown at 25, so that it may rock 25 upon the pivot 18. This dog or pawl 24 might of course be operated at will by any suitable connection extending to the exterior of the furnace; but inasmuch as it will require considerable power to rotate the grate in large 30 furnaces and it is desirable to have the sections of the grate successively presented opposite the stoking-aperture or fire-door when the door is opened for the introduction of fuel I prefer to effect the movement of the grate 35 by some suitable motor or engine and to simultaneously open the fire-door, so that the fireman may simultaneously open the door and present a new section of the grate for the reception of fresh fuel without giving special 40 thought to the operation. To this end I connect the dog 23 to a pull-bar 26, whose outer end may be carried through a suitable aperture in the furnace-wall and is pivoted to a 45 rocker-shaft 31, secured by boxes or straps 32 to the wall of the furnace and having at its other end a slotted crank 33, in the slot of which works a stud 34, formed on the end of a piston-rod 35, projecting from a steam-cylinder 36. By this means it will be seen that 50 when the piston-rod 35 is forced upwardly the rod 26 will be pulled outwardly. The outer end of the rod 26 is curved upwardly toward its pivotal connection with the arm 55 30, so as to permit of the necessary movement without causing the rod 26 to strike against the upper edge of the ash-door opening, as will be understood.
- In order now that this same movement may 60 open the fire-door 37, I provide the rocker-shaft 31 with an additional crank-arm 38, which is connected by a short link 39 with a crank-arm 40, projecting outwardly from the hinge-pintle 41, to which the door 37 is secured. Steam may be turned into the cylinder 36 in any suitable way, but this is prefer- 65 ably accomplished by means of a depressible

foot-piece 42, pivoted to the floor or other suitable support and having a rocker-shaft 43, which also constitutes the stem of a two-way valve or cock 44, which governs the inlet-pipe 45 and the exhaust-pipe 46, so that when the foot-piece 42 is depressed the steam will be admitted to the cylinder 36 for raising the piston-rod 35, and when the foot is removed from the foot-piece it will be raised by a spring 47, turning the exhaust-port of the plug into communication with the cylinder, the weight of the door 37 in the meanwhile causing such door to close and also returning the end 23 of the dog or pawl to the rear extremity of its movement and enabling it to engage with another one of the teeth 22. In the drawings the fire-door is shown partially open and the grate partially turned. 85

Extending athwart the fire-box and also across the forward or stoking side of the grate immediately over the fire-door opening is a crown or arch 49, which projects rearwardly in the fire-box about half the length or diameter thereof. The purpose of this crown or arch is to effect a thorough coking of the coal or fuel when it is introduced into the fire-box and before it has been conveyed to the hotter region of the fire-box by the rotation of the 95 grate.

Having thus described my invention, what I claim as new, and desire to secure by Letters Patent, is—

1. A furnace having in combination a fire- 100 box provided with a door; a rotatable grate; means connected with said door and having operative relation to said grate whereby the movement of the door will effect the movement of the grate; a foot-piece; and means 105 having operative relation to said foot-piece and door whereby the movement of the foot-piece simultaneously effects the movement of the door and grate, substantially as set forth.

2. A furnace having in combination a fire- 110 box provided in its vertical side with a stoking-aperture, a gravitating door closing said aperture, a rotatable grate having teeth or notches, a pivoted dog or pawl engaging with said teeth or notches, and being connected 115 with said door whereby the gravitation of the door will move said dog in one direction, an engine having a piston and piston-rod connected with said door for raising it, a valve for admitting pressure to said engine, a foot-piece for moving said valve in one direction and causing said engine to raise said door and means for automatically moving said valve in the other direction for permitting the door to close, substantially as set forth. 125

3. A furnace having in combination a fire- 130 box provided with a stoking-aperture, a door closing said aperture; a rotary grate composed of independently-dumping sections; ratchet-teeth having operative relation to said grate; a pawl arranged to engage with said teeth for rotating said grate, and a connection between said pawl and door whereby the opening of the door will rotate the grate, said ratchet-

teeth being so disposed and the stroke of the pawl so proportioned with relation to the position of the stoking-aperture and the movement of the door that each time the door is opened the grate will be rotated the distance of one section and each section will be successively brought completely opposite the door whereby the fuel thrown in will lodge

substantially upon only the section opposite the door, substantially as and for the purposes to set forth.

H. E. WALLIS.
